HOT GAS DEFROSTING

Alwin B. Newton, Minneapolis, Minn., assignor to
 Minneapolis-Honeywell Regulator Company,
 Minneapolis, Minn., a corporation of Delaware

Application April 30, 1942, Serial No. 441,127

17 Claims. (Cl. 62—115)

1

The present invention relates to improved automatic means and arrangements for defrosting the evaporators of refrigerating systems, particularly direct expansion systems.

The primary object of this invention is to provide means for accomplishing quick and efficient defrosting of an evaporator by admitting hot refrigerant into the evaporator, allowing it to condense therein and then pumping it out.

A more specific object of the invention in connection with the preceding object is to provide a restricted orifice means through which the condensed refrigerant is pumped out of the evaporator, the small size of the orifice causing a slow equalization of the pressures across the orifice for permitting all of the refrigerant to evaporate in the evaporator and not pass over to the compressor as a liquid.

Although this invention may be practiced in systems having but a single evaporator, it finds its widest use in multiple evaporator systems where the evaporators will be defrosted at different times thus assuring that an ample amount of hot refrigerant gas will be available for defrosting purposes.

Another object is to provide a timing mechanism for producing intermittent defrosting cycles, the timing mechanism providing for, in sequence, isolating the evaporator or evaporators to be defrosted and opening a valve admitting hot refrigerant gas to the unit or units to be defrosted, and after the defrosting periods, again in sequence, closing the hot refrigerant valve, opening the restricted orifice means for pumping out the evaporator, and then placing the evaporator or evaporators back in normal flow relationship with the system. Each evaporator may be provided with such a timing means and the timing means so arranged that not more than a certain percentage of the total number of evaporators could be defrosted at one time.

Numerous other objects and advantages of my invention will become apparent from the following detailed description and annexed drawing, the drawing comprising a single figure which illustrates, more or less diagrammatically, a refrigeration system embodying the various features of my invention.

The invention is directed mainly, although not exclusively, to defrosting of refrigerating units utilized in cold storage plants. Referring to the drawing, numeral 9 designates a refrigerating unit and controls therefor, forming part of a system which may be employed for refrigerating

storage chambers or the like. The unit 9 includes an evaporator 10 forming a part of a direct expansion refrigeration system and a motor driven fan 11 arranged to circulate air over the evaporator. Other units are indicated at 9a and 9b which also include an evaporator and fan. The evaporators are preferably within a duct or a housing through which air is circulated by the fan. The refrigerating system includes a compressor 12 which is driven by an electric motor, the discharge of the compressor being connected to a condenser 13 by a pipe 14. The condenser is connected to a liquid receiver 15 by a pipe 16 and the receiver 15 is connected to the evaporators of the units 9, 9a and 9b by pipes 18, 19, 19a and 19b. The outlets of the evaporators are connected to the suction side of the compressor by pipes 17, 17a and 17b, these pipes having various branch pipes connected to them which will be referred to presently.

Interposed in the pipe 19, that is in the liquid line leading to the evaporator 10, is a solenoid type stop valve 20 and beyond this valve is a thermostatic expansion valve 21 of the well known type which maintains a predetermined degree of superheat at the outlet of the evaporator. The valve 21 includes operating mechanism having expandible and contractible chambers one of which is connected to a thermal bulb 22 by means of a capillary tube 23, the thermal bulb being disposed in intimate heat exchange relationship with the pipe connected to the outlet of the evaporator, that is the suction pipe 17. The bulb 22 is filled with a volatile liquid which vaporizes and develops a pressure depending upon the temperature of the refrigerant gas in the outlet of the evaporator. The other expandible chamber of the operating mechanism of valve 21 is connected by a tube 24 to the outlet pipe 17 of the evaporator, the tube 24 being known in the art as an external equalizer connection, the pressure in the outlet pipe of the evaporator being utilized as one of the operating forces for the valve 21. The operation of valves of this type is well known in the art and need not be described in further detail.

Interposed in the suction line 17 is another solenoid type stop valve 27, it being understood, of course, that the valves 20 and 27 operate between open and closed positions in response to energization and deenergization of an electrical circuit.

Numeral 28 designates a by-pass connection connected to the pipe 17 so as to form a by-pass

around the valve 27. Interposed in the by-pass connection 28 is another solenoid stop valve 29 and this valve controls a relatively small orifice providing for a restricted flow of refrigerant through the by-pass 28 when the valve 29 is open.

Numer 30 designates a pipe forming a connection between the pipe 14 and the suction line or pipe 17. Interposed in the pipe 30 is a solenoid stop valve 31 and when this valve is open, hot refrigerant gas from the condenser and the compressor can pass freely through the pipe 30 to the pipe 17 and directly into the evaporator. The purpose of the by-pass 28 and the pipe 30 will be described more in detail hereinafter.

The system is provided with controls for normally starting and stopping the flow of refrigerant to the evaporator in response to the demands for cooling, and controls are also provided for initiating defrosting cycles at predetermined timed intervals. The purpose of the defrosting cycles, of course, is to remove accumulated frost and ice from the evaporator. Initiation of a defrosting cycle produces particular operation of the system to defrost the evaporator in the most efficient and expeditious manner as will presently be described.

The defrosting control mechanism includes a time operated switching device 35, this device having a switch arm 36 which may engage either one of two fixed electrical contacts 37 and 38. The blade 36 and its two associated contacts control an electric motor 39 through wires 40, 41 and 42, the motor 39 being of a well known type which always operates in the same direction, operating its shaft through 180° whenever the contacts make on one side or the other. Power for operation of the motor 39 is supplied by a step down transformer 43 having a primary winding 44 and a secondary winding 45, the primary winding being connected to line conductors 46 and 47 by wires 48 and 49 respectively. The line conductors 46 and 47 are connected to any suitable source of power not shown. It is contemplated that various other types of timers may be substituted, or if desired, a single timer may be substituted for the timer 35 and motor 39.

The motor 39 drives a shaft 53 through a gear train so that the shaft is rotated at a relatively low speed. Mounted on the shaft 53 are a number of cams which are indicated by the numerals 54, 55, 56, 57, 58 and 59. Each of the cams has a single dwell as shown and with the parts in the position as shown on the drawing the cams are in their initial position as far as operation of the motor 39 is concerned, and with the parts in this position, the dwells are angularly spaced with respect to the shaft 53 as shown.

The cam 54 cooperates with a pivoted switch carrying lever 60 carrying mercury switch 61 and with the parts in the positions shown, that is the initial position, the dwell or cam 54 is engaging the lever 60 so as to tilt it in a counter-clockwise direction so that the mercury switch is closed, its electrodes being at its left end.

The cams 55 and 56 both operate a single mercury switch 62 mounted on a switch carrying member 63 having downwardly extending cam follower portions 64 and 65. The cam follower portion 64 is associated with cam 55 and the cam follower portion 65 is associated with the cam 56, the arrangement being as diagrammatically shown on the drawing. As actually constructed, of course, the member 63 is arranged substantially at right angles to the shaft 53 and the portions 64 and 65 are slightly offset from each other so

as to be engageable with their respective cams, which, of course, are spaced on the shaft 53. The member 63 is frictionally mounted on a pivot 67, or it may be freely mounted and the switch 62 held in its actuated position due to its over center type of mounting. With the parts in the position shown the member 63 is rotated in a counter-clockwise direction on its pivot so as to cause closure of mercury switch 62, this switch having its electrodes at its left end. When the cams are rotated in a clockwise direction the dwell of cam 56 will move away from portion 65 leaving member 63 in the same position, but when the dwell of cam 55 engages portion 64, member 63 will be rotated in a clockwise direction so as to open mercury switch 62. This will occur after something less than 180° of rotation of shaft 53 in a clockwise direction, and upon continued rotation of shaft 53 the dwell of cam 56 will engage portion 65 so as to tilt member 63 in the opposite direction for closing mercury switch 62.

Numer 70 designates another mercury switch mounted on a member 71 of the same construction as member 63. Member 71 is mounted on a pivot 72 and has downwardly extending cam follower portions 73 and 74 cooperable with the cams 57 and 58 which are identical with the cams 55 and 56 respectively, and they operate mercury switch 70 in the same manner as the mercury switch 62 is operated.

Cam 59 has a single dwell and this cam actuates a pivoted switch carrying lever 77 carrying double ended mercury switch 78, that is a mercury switch having electrodes at both ends. With the parts in the position shown, lever 77 is tilted in a counter-clockwise direction and the electrodes at the left end of mercury switch 78 are bridged.

The timer 35 is arranged to operate the motor 39 to cause it to operate from an initial position through 180° of rotation of shaft 53 and then back to initial position, these operations occurring at intervals which may be spaced so that they may occur three or four times daily, for example, it being understood that this will cause defrosting operation of the refrigerating system three or four times during a day. The timer is arranged to cause blade 36 to engage contact 37 at these intervals and when it does so, motor 39 will operate to drive shaft 53 in a clockwise direction through 180°. The timer 35 as pointed out above causes blade 36 to engage contact 37 at intervals occurring three or four times daily and the timer is so adjusted that after blade 36 has engaged contact 37, approximately 12 minutes later the blade 36 will engage contact 38. The motor 39, as pointed out above, is of a type which always operates in the same direction, in this instance this being a clockwise direction and the motor 39 is arranged so as to require substantially four minutes to operate the shaft 53 through 180°. When blade 36 of the timer has engaged contact 37, motor 39 operates shaft 53 in a clockwise direction as pointed out, and upon this occurring, rotation of cam 54 substantially immediately allows mercury switch 61 to open. After substantially three minutes, the dwell of cam 55 engages portion 64 of member 63 rotating member 63 so as to open mercury switch 62. At the same time mercury switch 70 is opened in the same manner by cam 57. Substantially at the end of the four minute period required for shaft 53 to turn through 180° the dwell of cam 59 engages lever 77 so as to tilt it causing the mercury in mercury switch 78 to move to the other end of the switch bridging the electrodes at the right end and un-

70 75

bridging the electrodes at the left end. The parts will remain in this position for approximately 8 minutes at the expiration of which time blade 36 will have engaged contact 38 so as to reenergize the motor 39 causing the shaft 53 to be rotated another 180° in a clockwise direction, this rotation also requiring substantially 4 minutes. Upon this rotation, substantially immediately, cam 59 will allow the electrodes at the left end of mercury switch 78 to be bridged and the electrodes at the right end to be unbridged. After substantially three minutes of this period of rotation of shaft 53 have elapsed cam 58 will be in a position to engage portion 74 of member 71 so as to rotate this member in a counter-clockwise direction so as to close mercury switch 70. At the same time cam 56 will cause closure of mercury switch 62. Substantially at the end of this four minute period of rotation cam 54 will cause closure of mercury switch 61.

The timer 35 may be any of various types of interval timers already known in the art and includes a time switch adjustment knob 34.

Any timing device would suffice which would make the contacts on one side three or four times daily with the contacts on the other side being made substantially twelve minutes later in each instance. Momentary closure of the contacts is sufficient inasmuch as the motor 39 includes maintaining switches and circuits controlled by the motor itself.

During normal operation, the evaporator 10 is controlled by opening and closing the stop valve 20 in the liquid line 16. This valve is controlled by a thermostat 80 comprising a bi-metal element 81 arranged to actuate a movable switch blade 82 which moves into engagement with and out of engagement with a fixed electrical contact 83. The thermostat 80 is located in the storage compartment being refrigerated and it may cause its contacts to make at any desired temperature, for instance 40°.

The motor driving the compressor 12 is controlled by a suction pressure controller 84 which comprises a switch controlling a circuit including a wire 85 leading to the compressor motor, a wire 86 and a wire 87, the wires 85 and 87 being connected to any suitable source of power not shown. The suction pressure controller 84 includes an expansible and contractible member connected to the suction line 17 by a pipe 88, it being understood, of course, that the switch of the suction pressure controller closes to start the compressor at a predetermined relatively high pressure in the suction line and opens the switch to stop the compressor in response to a predetermined relatively low pressure in the suction line.

The units 9a and 9b are each provided with controls which may be duplicates of the controls described above for the unit 9. The timers are so adjusted, however, by time switch adjustment knobs 34, 34a and 34b, so that only one evaporator is defrosted at a time by setting said knobs with more than twelve minute intervals between them. Thus the closing of one inlet valve 20 will rarely cause such a reduction in suction pressure as to cause deenergization of the compressor and hence there will nearly always be an ample supply of hot refrigerant gas in the pipe 14. The units 9a and 9b are connected to the hot refrigerant line 14 by means of conduits 30a and 30b respectively.

With the parts in the position shown, the system is operating normally and under these circumstances all of the mercury switches are closed with the exception of the switch formed by the

right hand electrodes of mercury switch 78. The stop valve 27 in the suction line is open, this valve being controlled by mercury switch 70, and its circuit being as follows: from line conductor 47 through wire 90, mercury switch 70, wire 91, valve 27, and wire 92 back to line conductor 46. The stop valve 29 in the by-pass connection 28 is also open, this valve being controlled by the electrodes at the left end of mercury switch 78 which are bridged at this time, the circuit for valve 29 being as follows: from line conductor 47, through wire 93, the left end of mercury switch 78, wire 94, valve 29 and wire 95 back to line conductor 46. The valve 31 controlling the hot gas connection 30 is closed at this time, this valve being controlled by the electrodes at the right end of mercury switch 78.

The solenoid valve 20 in the liquid line as pointed out, is controlled by mercury switch 61 and thermostat 80 and with the parts in the position shown mercury switch 61 is closed and the contacts of thermostat 80 are made indicating a demand for refrigeration so the valve 20 is energized through the following circuit: from line conductor 47 through wire 97, mercury switch 61, wire 98, contact 83, blade 82, element 81, wire 99, valve 20 and wire 100 back to line conductor 46. Valve 20 being open, liquid refrigerant is admitted to the evaporator from condenser 13 and receiver 15 and inasmuch as the valve in the suction line is open the compressor is able to pump evaporated refrigerant out of the evaporator. The switch of the controller 84 is closed causing the compressor 12 to operate. The fan 11 is in operation for circulating air over the evaporator of unit 10, the operation of fan 11 being controlled by mercury switch 62 and its circuit being as follows: from line conductor 47 through wire 101, mercury switch 62, wire 102, the motor of fan 11, and wire 103 back to line conductor 46.

The system will operate under these circumstances to maintain a predetermined temperature in the refrigerated compartment, the controller 84 acting to stop the compressor whenever the suction pressure is reduced to a predetermined value.

When the timer 35 causes blade 36 to engage contact 37 at one of the spaced intervals, as described above, motor 39 will be energized causing shaft 53 to operate in a clockwise direction for substantially four minutes as described above. Mercury switch 61 will be opened substantially immediately so as to deenergize and close valve 20 so as to stop the flow of refrigerant to the evaporator 10. When valve 20 is closed the compressor will, of course, pump down the evaporator relatively quickly. The suction pressure will not be lowered sufficiently to stop the compressor at this time due to the fact that the units 9a and 9b are still in operation. As pointed out above, after the motor 39 has operated for substantially 3 minutes, for example, cams 55 and 57 will open mercury switch 62 and 70 respectively thus stopping the fan 11 and closing the stop valve 27 in the suction line 17. As pointed out above substantially at the end of the four minute period cam 59 will cause the electrodes at the left end of mercury switch 78 to be unbridged and the electrodes at the right end to be bridged. This will cause closure of the valve 29 in the by-pass 28 and opening of valve 31 in the connection 30. With the valves 20, 27 and 29 closed the evaporator is isolated from the system as far as the normal circulation of refrigerant is concerned. With the valve 31 open, hot gas from the condenser is permitted to

flow freely into the evaporator through pipe 30 and pipe 17. This hot gas upon entering the evaporator will condense, thereby giving up a considerable amount of heat which will serve to defrost the evaporator. The defrosting action will be allowed to continue for substantially an 8 minute period, the motor 39 as pointed out above remaining in its position wherein the mercury switches are open for a period of substantially 8 minutes. At the end of this period, blade 36 of the timer will engage contact 38 reenergizing the motor 39 causing it to again operate for a period of substantially 4 minutes, the motor again operating in a clockwise direction. Substantially at the beginning of this 4 minute period cam 59 will operate mercury switch 78 to the position shown on the drawing, wherein the circuit of valve 31 is interrupted for closing this valve and the circuit of valve 29 is reenergized for opening this valve. Valve 27 will remain closed for a period of perhaps 3 or 3½ minutes while valve 29 is open and shaft 53 is rotating. Opening of valve 29 will, of course, permit refrigerant to pass through its restricted orifice to provide for the gradual decrease in pressure in the evaporator which will give practically all of the condensed refrigerant time enough to evaporate and pass through the valve 29 as a gas. This being an upfeed evaporator it may be desirable to provide a restricted bypass 105 and check valve 106 around the valve 20 and expansion valve 21 to provide any liquid refrigerant which may accumulate in the bottom of the coil an opportunity to pass into the high side of the line 19. The pressure in pipe 19 will be slightly lower than that in the evaporator when valve 20 is closed and valve 31 open. The purpose, therefore, of the valve 29 with its small orifice is to prevent any liquid refrigerant from entering the compressor after the evaporator has been defrosted.

After substantially 3 or 3½ minutes, for example, of the last mentioned 4 minute period have elapsed, cams 56 and 58 will cause closure of mercury switch 62 and 70 respectively in the manner described above. This will cause restarting of the fan 11 and reopening of the stop valve 27 in the suction line. Substantially at the end of the 4 minute period, cam 54 will reclose mercury switch 61 putting valve 20 back under control of thermostat 80 and if there is a demand for a refrigeration at the time valve 20 will be opened and the system will again operate normally.

As set forth above, the other two units 9a and 9b are defrosted in the same manner but the timers are so arranged or adjusted that no two units are defrosted at the same time. A total of three units are disclosed herein but it will be readily appreciated that my invention is applicable to a system employing any number of units, and may be successfully employed in a system having one unit.

Those skilled in the art will appreciate from the foregoing that the system herein disclosed provides an efficient and expeditious method of defrosting an evaporator wherein the defrosting operation is so arranged and sequenced that the refrigerant used for defrosting is not returned to the compressor in the form of liquid.

The form of my invention, which I have disclosed, is representative and it will be understood that various modifications and changes will occur to those skilled in the art. The disclosure is illustrative and the invention is to be limited only in accordance with the claims appended hereto.

I claim as my invention:

1. In apparatus of the character described, in combination, means forming a refrigerating system including an evaporator and a source of refrigerant supply normally connected in refrigerant flow relationship, said source being capable of supplying hot refrigerant, defrosting apparatus comprising means for closing the liquid and suction lines of the evaporator, means for communicating hot gas from the said source directly to the evaporator so that said gas may condense in the evaporator for defrosting it, and means forming a relatively restricted orifice connecting said source and evaporator by which refrigerant used for defrosting is withdrawn from the evaporator and returned to the inlet of said source, the restricted orifice acting to prevent refrigerant in liquid form from returning to said inlet.

2. In apparatus of the character described, in combination, means forming a refrigerating system comprising a refrigerant evaporator and a source of refrigerant normally connected in refrigerant flow relationship, said source being capable of supplying hot refrigerant, means for isolating said evaporator as far as said normal flow relationship is concerned, means by which hot refrigerant from said source is communicated to said evaporator for defrosting it, said refrigerant being returned to the source when the evaporator is again placed in normal refrigerant flow relationship with the source of refrigerant, and automatic defrosting control means for operating said isolating means and communicating means upon a demand for defrosting and for causing said communicating means to cut off the flow of hot refrigerant after defrosting.

3. In apparatus of the character described, in combination, means forming a refrigerating system comprising a refrigerant evaporator and a source of refrigerant normally connected in refrigerant flow relationship, said source being capable of supplying hot refrigerant, means for isolating said evaporator as far as said normal flow relationship is concerned, means by which hot refrigerant from said source is communicated to said evaporator for defrosting it, means having a relatively restricted orifice through which refrigerant used for defrosting is returned to the inlet of the source, the restricted orifice acting to prevent refrigerant in liquid form from returning to said inlet, and automatic defrosting control means for operating said isolating means and communicating means upon a demand for defrosting and for causing said communicating means to cut off the flow of hot refrigerant after defrosting before the refrigerant used for defrosting is returned to the source through said restricted orifice means.

4. In apparatus of the character described, in combination, means forming a refrigerating system comprising a refrigerant evaporator and a source of refrigerant normally connected in refrigerant flow relationship, said source being capable of supplying hot refrigerant, means for isolating said evaporator as far as said normal flow relationship is concerned, means by which hot refrigerant from said source is communicated to said evaporator for defrosting it, means having a relatively restricted orifice through which refrigerant used for defrosting is returned to the inlet of the source, the restricted orifice acting to prevent refrigerant in liquid form from returning to said inlet, and automatic defrosting control means comprising timing means for sequentially operating the isolating means and communicating means upon a demand for defrosting and for

causing the communicating means to cut off the flow of hot refrigerant after defrosting before the refrigerant used for defrosting is returned to the source through said restricted orifice means.

5. In apparatus of the character described, in combination, a refrigerating system including a compressor, condenser and expander connected in refrigerant flow relationship, valve means for closing the liquid and suction lines of the expander, means for conveying hot refrigerant to the expander when said valve means are in closed position, and means having a relatively restricted orifice connecting said expander and the suction side of said compressor through which refrigerant may be withdrawn from the expander by said compressor when said valve means are in closed position.

6. In apparatus of the character described, in combination, a refrigerating system including a compressor, condenser and expander connected in refrigerant flow relationship, valve means for closing the liquid and suction lines of the expander, connections for conveying hot refrigerant to the expander when said valve means are in closed position, and a passage having a valve means associated with a relatively restricted orifice connecting said expander and the suction side of the compressor through which refrigerant may be withdrawn from the expander when said valve means are in closed position, said valve means including a stop valve in the suction line and said passage having a valve means associated with a restricted orifice being arranged in by-pass relationship with said stop valve in the suction line.

7. A refrigeration system comprising in combination, refrigerant compressor means, a plurality of evaporators, means for condensing the compressed refrigerant, means conducting condensed refrigerant from said condensing means to the inlet of each of said evaporators, means connecting the outlet of each of said evaporators to the suction side of said compressor means, and means for defrosting at least one of said evaporators, said last named means including means for preventing the flow of condensed refrigerant to the inlet of said evaporator, means conducting hot compressed refrigerant gas to said evaporator for heating the same and means adjustable to prevent all of said evaporators from being defrosted at the same time whereby hot refrigerant gas will be available for defrosting purposes whenever said compressor is operating.

8. The method of defrosting a refrigerating system of the type including a compressor, a condenser and an evaporator, comprising, closing off communication between the inlet of the evaporator and the condenser and between the outlet of the evaporator and the suction side of said compressor and supplying hot gaseous refrigerant to the evaporator through its outlet directly from the compressor until the evaporator is defrosted, then discontinuing the supply of hot gaseous refrigerant to the evaporator and connecting said evaporator to the suction side of the compressor through a restriction to gradually remove the refrigerant in the evaporator, and finally establishing normal communication between the inlet of the evaporator and the condenser and between the outlet of the evaporator and the suction side of the compressor.

9. The method of defrosting a refrigerating system of the type including a compressor, a condenser and an evaporator, comprising, first closing off communication between said condenser

and the inlet of the evaporator while the compressor is operating so that the refrigerant in said evaporator is removed therefrom, then closing off communication between the outlet of the evaporator and the suction side of said compressor and supplying through the outlet of the then isolated evaporator hot gaseous refrigerant directly from the high side of said compressor, then discontinuing the supply of hot gaseous refrigerant to the evaporator and connecting the outlet of the evaporator to the suction side of the compressor through a restriction to gradually remove the refrigerant in the evaporator, and finally establishing normal communication between the inlet of the evaporator and the condenser and between the outlet of the evaporator and the suction side of the compressor.

10. A defrosting arrangement for a refrigeration system of the usual compressor, condenser, and evaporator type, comprising, in combination, liquid line valve means operable to establish or close off communication between the condenser and the inlet of the evaporator, suction line valve means operable to establish or disrupt communication between the outlet of said evaporator and the suction side of said compressor, a by-pass around said suction line valve, said by-pass including valve and restrictor means, gaseous refrigerant valve means operable to establish or close off communication between the outlet of said compressor and said evaporator, and sequence means in control of said valve means to first operate said liquid line valve means to prevent communication between said condenser and evaporator and thereafter to operate said suction line valve means and said gaseous refrigerant valve means to prevent communication between said evaporator and the suction side of said compressor and to establish communication between the outlet of said compressor and said evaporator to supply hot gaseous refrigerant to said evaporator to defrost the same and then to close said gaseous refrigerant valve and to open the valve means in said by-pass.

11. A defrosting arrangement for a refrigeration system of the usual compressor, condenser, and evaporator type, comprising, in combination, liquid line valve means operable to establish or close off communication between the condenser and the inlet of the evaporator, suction line valve means selectively operable to establish full or restricted communication or to disrupt fully communication between the outlet of said evaporator and the suction side of said compressor, gaseous refrigerant valve means operable to establish or close off communication between the outlet of said compressor and said evaporator, and sequence means in control of said valve means operable first to operate all of said valve means to close off communication from the evaporator to the condenser and suction side of the compressor and to establish communication between the outlet of the compressor and the evaporator, to thereafter operate said gaseous refrigerant valve means to close off communication between the outlet of the compressor and the evaporator and to establish restricted communication between the outlet of the evaporator and the suction side of the compressor, and to finally reestablish full communication from the condenser to the evaporator and thence to the suction side of the compressor.

12. A defrosting arrangement for a refrigeration system of the usual compressor, condenser, and evaporator type, comprising, in combination,

Liquid line valve means operable to establish or close off communication between the condenser and the inlet of the evaporator, suction line valve means selectively operable to establish full or restricted communication or to disrupt fully communication between the outlet of said evaporator and the suction side of said compressor, gaseous refrigerant valve means operable to establish or close off communication between the outlet of said compressor and said evaporator, and sequence means in control of said valve means operable to first operate said liquid line valve means to prevent communication between said condenser and evaporator, to thereafter operate said suction line valve means and said gaseous refrigerant valve means to prevent communication between said evaporator and the suction side of said compressor and to establish communication between the outlet of said compressor and said evaporator, to then operate said gaseous refrigerant valve means to close off communication between the outlet of the compressor and the evaporator and to establish restricted communication between the outlet of the evaporator and the suction side of the compressor, and finally to re-establish full communication from the condenser to the evaporator and thence to the suction side of the compressor.

13. In apparatus of the character described, in combination, means forming a refrigerating system including an evaporator and a source of refrigerant supply normally connected in refrigerant flow relationship, said source being capable of supplying hot refrigerant, cyclically operated means for closing the liquid and suction lines of the evaporator to stop said normal refrigerant flow relationship, and means for supplying hot gas from the said source directly to the evaporator while said normal refrigerant flow is stopped so that said gas may condense in the evaporator for defrosting it.

14. In a refrigerating system, in combination, an evaporator, a source of refrigerant, said source being capable of supplying hot refrigerant, means connecting said evaporator and said source in normal refrigerant flow relationship, means for preventing normal refrigerant flow through said evaporator, means for supplying hot refrigerant from said source directly to said evaporator for defrosting the same, and means including a restriction for returning refrigerant used for defrosting to said source.

15. In apparatus of the character described, in combination, means forming a refrigerating system comprising a refrigerant evaporator and a source of refrigerant normally connected in refrigerant flow relationship, said source being capable of supplying hot refrigerant, means for positively isolating said evaporator as far as

said normal flow relationship is concerned, means for introducing hot refrigerant from said source to the isolated evaporator for defrosting it, and means having a relatively restricted orifice connecting the evaporator to said source through which refrigerant used for defrosting is returned directly to the inlet of the source only after the introduction of hot refrigerant to said evaporator has ceased, the restricted orifice acting to prevent refrigerant in liquid form from returning to said inlet.

16. In apparatus of the character described, in combination, means forming a refrigerating system comprising a refrigerant evaporator and a source of refrigerant normally connected in refrigerant flow relationship, said source being capable of supplying hot refrigerant and having an inlet, means for isolating said evaporator from said normal flow relationship including a valve for controlling flow between said evaporator and said inlet, means by which hot refrigerant from said source is communicated to said evaporator for defrosting it, and conduit means including a fluid flow restriction connected in by-pass relation to said valve through which refrigerant used for defrosting may be returned to said source.

17. In apparatus of the character described, in combination, means forming a refrigerating system comprising a refrigerant evaporator and a source of refrigerant normally connected in refrigerant flow relationship, said source being capable of supplying hot refrigerant and having an inlet, means for isolating said evaporator from said normal flow relationship including a suction valve for controlling flow between said evaporator and said inlet, means by which hot refrigerant from said source is communicated to said evaporator for defrosting it, and conduit means including a fluid flow restriction and valve means connected in by-pass relation to said suction valve through which refrigerant used for defrosting may be returned to the said source.
